WEB TENSIONING DEVICE

Herbert A. Lotz, Minneapolis, Minn., assignor to
 Wood Newspaper Machinery Corporation,
 Plainfield, N. J., a corporation of Virginia

Application July 24, 1939, Serial No. 286,102

10 Claims. (Cl. 242—75)

My present invention relates to the control of a roll of web material and the tensioning of its web between said roll and a printing press or other machine into which the web is fed. This invention, while intended for general use, is especially well adapted for use in connection with a modern rotary printing press where the high efficiency thereof can only be obtained, in the production of a high quality product, by the proper tensioning of the paper web from the time it leaves the live roll of paper until it is drawn into the printing press, and with the least possible chance of interruption, due to mechanical failure, a badly wound roll of paper, and the like.

It is well known that the braking effort required to control a roll of paper progressively decreases in proportion to the diameter of the roll as the same is progressively decreased by the unwinding of the web from said roll.

It is also well known that the web tension, during normal running speed of a printing press, and during acceleration or deceleration of the speed thereof, should remain constant, and that to control that uniformity of web tension, a variable and automatic, as well as manual means could be applied, and in case of sudden stopping of the printing press, to prevent the roll from running ahead under momentum and thereby put slack in the web, more braking effort is required.

It is an object of this invention to provide a friction braking member having a circumferential wrap with the periphery of a roll of paper, and for holding said member with a minimum braking effort on the roll when the printing press is stopped, for progressively and automatically increasing this braking effort during acceleration of the printing press, for holding said member with a constant and predetermined braking effort on the roll during normal running of the printing press, and for progressively and automatically decreasing the braking effort during deceleration of the printing press.

A further object of the invention is to progressively decrease the circumferential wrap of the braking member on the roll in proportion to the progressively decreasing diameter of the unwinding roll, as in relation to the full roll.

A still further object of the invention is to automatically increase the braking effort of the friction member on the roll above that applied during normal running of the printing press in case tension on the web is suddenly reduced.

Other objects of the invention will be apparent from the following description, reference being had to the accompanying drawings.

To the above end, generally stated, the invention consists of the novel devices and combinations of devices hereinafter described and defined in the claims.

In the accompanying drawings, which illustrate

the invention, like characters indicate like parts throughout the several views.

Referring to the drawings:

Fig. 1 is a view partly in end elevation and partly in section taken substantially on the line 1—1 of Fig. 2;

Fig. 2 is a fragmentary rear elevation with the basement and sub-basement floors sectioned substantially on the irregular line 2—2 of Fig. 1;

Fig. 3 is a view principally in plan with some parts sectioned on the line 3—3 of Fig. 1;

Fig. 4 is a detail view partly in side elevation and partly in section taken on the line 4—4 of Fig. 3, on an enlarged scale;

Fig. 5 is a detail view partly in end elevation and partly in section taken on the line 5—5 of Fig. 4;

Fig. 6 is a left-hand end elevation of certain parts shown in Fig. 4;

Fig. 7 is a fragmentary detail view partly in plan and partly in section taken on the line 7—7 of Fig. 4;

Fig. 8 is a detail view principally in section taken centrally and vertically through the combined reducing and relief valve shown in Fig. 1, above the upper floor;

Fig. 9 is a detail view principally in section taken centrally and vertically through the reducing valve shown in Fig. 1 between the two floors;

Fig. 10 is a fragmentary detail view showing one of the tension units as the same appears in Fig. 3, with the exception that the cable and weight are shown by means of full lines instead of broken lines, as shown in Figs. 1 to 4, inclusive;

Fig. 11 is a fragmentary detail view in rear elevation of the tension unit shown in Fig. 10; and

Fig. 12 is a fragmentary view corresponding in part to Fig. 1, but showing a modification of the roll-engaging friction member.

The numerals 14 and 15, indicate what may be assumed to be the basement and sub-basement floors, respectively, of printing press-rooms in a newspaper building, and the numeral 16 indicates a pit in the sub-basement floor 15.

As this invention relates only to the control of a roll of material, in the form of a web, as the same is being rotated by the unwinding of its web therefrom and the tensioning of its web from the time it leaves the live roll until it is drawn into the machine, it is not thought necessary to illustrate said machine, or any part thereof, except certain of its directional rolls over which the web travels from the live roll to the machine, as will hereinafter appear. Hereinafter, the machine will be referred to as a "printing press," and the roll of material as "a roll of paper."

The numeral 17 indicates a reel of a well-known commercial type and having a capacity for holding three rolls of paper, either full length,

three-quarters length or one-half length. This reel 17 has three sets of radial arms and each set thereof is provided with means for rotatably supporting a roll of paper thereon. The rolls of paper on the reel 17 are designated by the letters *x*, *y* and *z*, the roll *y* is the active or live roll, and its web *w* is being unwound therefrom by the operation of the printing press into which it is being drawn; and the rollers *x* and *z* are new rolls, the roll *z* being the next roll to be brought into position as the roll *y* expires.

The reel 17 further includes a shaft 18, about the axis of which said reel is rotated. This shaft 18 is journaled in end bearings 19 anchored to the floor 14 at the ends of the pit 16. To successively bring the rolls of paper on the reel 17 into active position, said reel is manually controlled and intermittently rotated by a pinion 20 driven by an electric motor, not shown, and which pinion meshes with a gear 21 keyed to the shaft 18 at one end thereof.

To bring the new roll *z* into active position, the reel 17 is rotated in the direction of the arrow marked on Fig. 1 of the drawings, between the rolls *y* and *x*, and at which time a so-called flying paster is made to connect the two webs of the rolls *y* and *z*.

From the roll of paper *y*, its web *w* passes over a directional roll 22, around a yieldingly held roll 23, under and around a directional roll 24, and from thence, said web passes through an opening in the floor 14 and over a directional roll 25 to the printing press. The directional rolls 22 and 24 are journaled in fixed bearings in brackets 26, only one of which is shown, secured to and depending from the under side of the floor 14. The yieldingly held roll 23 is journaled in bearings 27 slidably mounted in the brackets 26 and coiled springs 28, compressed between the brackets 26 and sliding bearings 27 yieldingly press the roll 23 away from the rolls 22 and 24. By reference to Fig. 1, it will be noted that the directional roll 24 is vertically spaced directly above the roll 22 and that the roll 23 is midway between the rolls 22 and 24 and spaced horizontally forwardly therefrom. The web *w* is unwound from the roll *y* at the back thereof and the directional roll 22 holds said web, as it leaves roll *y*, in an upwardly and forwardly inclined position.

The roll 23 holds the web *w* looped between the rolls 22 and 24 and the springs 28, as heretofore stated, are under strain to move the roll 23 away from the rolls 22 and 24 and thereby lengthen the loop in the web *w* and take up any slack in said web.

Or in other words the path of the center of roll 23 moves in a line perpendicular to a line drawn between the centers of rolls 22 and 24.

The parts thus far described, except for the spring pressed roll 23, are of standard and well known construction.

Referring now in detail to the invention, which, as shown, includes four separate and distinct tension units. Each tension unit, as shown, includes an endless friction belt 29 that runs over upper, lower and intermediate directional devices which, as shown, are flanged pulleys 30, 31 and 32, respectively. The upper pulley 30 is fixed to a shaft 33 journaled in bearings 34, only one of which is shown, secured to and depending from the under side of the floor 14. Said shaft 33 has a gear 35 fixed to one end thereof and driven by an electric motor or any other suitable means, not shown. It will be noted that the driven pulley

30 is materially above the active roll *y* and slightly rearwardly of a vertical line that passes through the axis about which said roll turns on the reel 17.

- 5 The lower pulley 31 is loosely journaled on a short shaft 36, the end portions of which are mounted in the side members of a yoke-like cross-head 37. This cross-head 37 is slidably mounted in a cross-head guide 38 in the form of a cylinder having upper and lower slots 39 which extend substantially the full length of said guide. The outer faces of the side members of the cross-head 37 have the same transverse curvature as the internal walls of the cross-head guide 38. 10 Said cross-head guide 38 holds the cross-head 37 for straight-line travel, and the pulley 31, which extends through both slots 39, prevents said cross-head from turning about its axis relative to the cross-head guide 38, and at the same time the pulley 31 is free to rotate about the axis of the shaft 36 and move bodily with the cross-head 37 during its endwise travel in the cross-head guide 38.

The cross-head guide 38 has on its sides a pair of angle-bar legs 40 which are anchored to the inclined rear wall of the pit 16. These legs 40 support the cross-head guide 38 in an upwardly and rearwardly inclined position, with its rear end portion in the pit 16, and with its axis aligned with a radial line extending from the axis of the pulley 32.

Mounted on the rear or upper end of the cross-head guide 38, in axial alignment therewith, is a cylinder 41 in which a co-operating piston 42 works. This piston 42 is connected by a rod 43 to the cross-head 37. A yoke 44 is secured to the rear ends of the side members of the cross-head 37 and extends transversely of and below the pulley 31, for a purpose that will presently appear.

The pulley 32 is fixed to an idle shaft 45 journaled in adjustable bearings on brackets 46 anchored to the floor 15 rearwardly of the pit 16. It is important to note the peculiar relation of the pulleys 30, 31 and 32 to each other and to the live roll of paper *y*, wherein the pulley 30 is materially above the roll *y*, the pulley 31 is materially below said roll, and the pulley 32 is substantially midway between the axis of the pulley 50 31 and the axis of the roll *y* and rearwardly of said roll. It is also important to note that the axis of the roll *y* is radially and rearwardly offset from a line extending from the axis of the pulley 30 to the axis of the pulley 31 in all of its 55 positions as set by the cross-head 37.

The run of the belt 29 from the pulley 31 to the pulley 30 has a segmental wrap, at its intermediate portion, around the roll of paper *y* at the back thereof, or in other words, the roll *y* holds the belt 29 rearwardly bowed between the pulleys 31 and 30. The end portions of this run of the belt 29 extend longitudinally from the roll *y* in diverging relation. The pulley 32 holds the two runs of the belt 29 that extend thereto and therefrom substantially at right angles to each other and out of contact with the run of said belt having frictional contact with the roll *y*. The belt 29 is driven in the direction of the arrows marked thereon in Fig. 1, by the pulley 30 on the driven shaft 33, and said belt and the web *w* leave the roll *y* at substantially the same point and in diverging relation.

It may be here stated that the belt 29 is preferably driven at a speed, say two per cent (2%) less than that of the lineal travel of the web *w*

and thus places a drag on the rotation of the roll *y*.

In addition to the spring-pressed roll *27* and the movable pulley *31*, the tension of the web *w* is further controlled by a floating governing roll *47* journaled on the free ends of a pair of arms *48* keyed to a rock shaft *49* journaled in bearings *50* anchored to the floor *14*. Fixed to the rock shaft *49* is a rod *51* which projects therefrom in the opposite direction from the arms *48*. Counterweights *52* are mounted on the rod *51* for adjustment toward or from the roll *47*. The floating governing roll *47* extends transversely of the web *w* and rests thereon between the rolls *24* and *25* above the floor *14*.

The counterweights *52*, as shown, are adjusted on the rod *51* for a full length roll of paper, but they may be adjusted for a three-quarter length roll or a one-half length roll. These counterweights *52* may also be adjusted relative to the governing roll *47* to cause said roll, which rests on the web *w*, to hold said web under a predetermined web tension and in balance.

To prevent the governing roll *47* from being lifted by the web *w* when given a sudden pull, for instance, when a new roll of paper is swung into contact therewith by the reel *17*, while being moved into active position, I provide a dashpot *53* containing a body of oil on which rests a plunger *54* loosely fitted in said dashpot. This plunger *54* is provided with a rod *55* which works through the top of the dashpot *53* and is loosely connected to the rod *51*. In the top of the dashpot *53* is an air relief port *56*.

The piston *42* is operated by fluid under a predetermined pressure to move the pulley *31* downwardly in the cross-head guide *38*, and take up the run of the belt *29* between the pulleys *30* and *31*, as the length thereof is progressively shortened by the diminishing diameter of the expiring roll *y* as its web *w* is unwound therefrom. This compressed fluid, hereinafter referred to as air, for the sake of convenience, is conveyed from a storage tank *57* to the cylinders *41* above their pistons *42* through a main pipe line comprising sections *58* and *58'*, and branch pipes *59* leading from the pipe sections *58'* to said cylinders. A hand valve *60* is interposed in each branch pipe *59*. Air is supplied to the storage tank *57* by a compressor *61* actuated by an electric motor *62*.

A valve casing *63* connects the pipe sections *58* and *58'* and mounted in said casing is a reducing valve *64* that may be set, at will, to tend to maintain a constant pressure in outlet pipe *58'* in accordance with the setting of valve *64*.

Also leading from the storage tank *57* is a pipe line comprising sections *65* and *65'*, the delivery end of the pipe section *65'* being connected into the pipe section *58'*, which is on the discharge side of the valve casing *63*.

Interposed in the pipe section *65*, (Fig. 8) above the floor *14* and under one of the arms *48*, is a valve casing *66* for an air-reducing valve and an air relief valve, and which casing comprises upper and lower sections between which a diaphragm *67* is clamped. This diaphragm *67* divides the valve casing *66* into an upper chamber *68* and a lower chamber *69*. Formed in the valve casing *66* is a port *70* which extends radially into the lower chamber *69* and forms a continuation of the pipe section *65* which leads from the storage tank *57* to the intake side of the valve casing *66*. The port *70*, at its inner end, is normally closed by an automatic air-reducing ball valve *71*, and the pipe section *65* leading

from the discharge side of the valve casing *66* is connected into the lower chamber *69*.

A sleeve-like assembly *72* is secured to the diaphragm *67*, and the opening therethrough affords a communicating port *73* between the two chambers *68* and *69*. An automatic air relief ball valve *74* normally closes the port *73*. Both valves *71* and *74* are mounted on a common carrier *75* in the lower chamber *69* and are arranged to close both ports *70* and *73* by an upward vertical movement thereof, and which ports are axially aligned with the valve casing *66* and with each other. A coiled spring *76*, mounted in a seat therefor in a screw plug *77* closing an opening in the bottom of the valve casing *66*, engages the lower end of the valve carrier *75* and yieldingly holds said carrier with the valves *71* and *74* positioned to close the respective ports *70* and *73*. In the walls of the upper section of the valve casing *66* is a plurality of air escape holes *78*. Within the upper chamber *68* is a coiled spring *79* which rests on the diaphragm *67*, and its lower end portion encircles the assembly *72* which affords a spring base therefor. On the upper end of the spring *79* is a spring cap *80* having at the axis of said spring a concave seat in which the rounded lower end of a push-rod *81* is seated. This push-rod *81* is axially aligned with the valve casing *66* and extends through a bushing in the top of said casing with freedom for endwise sliding movement. The push-rod *81*, at its upper end, is engaged by one of the arms *48* and may be depressed thereby to open the valve *74*, as will presently appear.

35 A valve casing *82* (Fig. 1) connects the two pipe sections *65* and *65'* and is provided with a lower valve chamber *83*, an upper valve chamber *84* and an axial passageway *85* connecting said two chambers. The pipe section *65* is connected 40 into the lower valve chamber *83*, and the pipe section *65'* is connected into the passageway *85*. Within the valve chamber *83* is an automatic valve *86* for opening and closing the air supply through the valve casing *82* from the pipe section *65* to the pipe section *65'*. An automatic relief valve *87* in the valve chamber *84* is provided for opening and closing the passageway *85*. These two valves *86* and *87* are carried on the rod *88* of a piston *89*, which works in a co-operating cylinder *90* mounted on top of the valve casing *82*. A relief port *91* in the valve casing *82* leads from the chamber *84* to atmosphere. This relief port *91* is simultaneously opened and closed with the passageway *85* by the relief valve *87*. The valves *86* and *87* are arranged to be alternately opened and closed and a coiled spring *92*, compressed between the bottom of the valve casing *82* and the valve *86*, is under strain to close the valve *86*, open the valve *87* and hold the piston *89* in its uppermost position.

Oil under pressure is provided for operating the piston *89* to open the valve *86* and close the valve *87* during the operation of the printing press. The system for supplying oil under pressure to the cylinder *90* includes a supply tank *93*, a pipe *94* leading from the tank *93* to the cylinder *90*, on the opposite side of the piston *89* from the valves *86* and *87*, and a return pipe *95* leading from said cylinder to the supply tank *93*. Interposed in the pipe *94* is a pump *96* for circulating oil from the supply tank *93* through the pipe *94*, cylinder *90* and pipe *95* to said tank. Connections *97* drive the pump *96* from a moving part of the printing press having a variable speed. A hand-operated cut-off valve *98* is in-

Bleed holes 78
Fig. 8, 56.1+

terposed in the pipe 95' to restrict its oil-conducting capacity and thereby cause the desired oil pressure to be built up in the cylinder 90 by the pump 96.

In place of operating the pulley 31 of each unit, by means of the air cylinder 41 and co-operating piston 42, the same may be operated by a weight 99 connected by a cable 100 to the yoke 44 on the cross-head 39. This cable 100 runs over a guide sheave 103 on the shaft 45, 10 see Figs. 10 and 11.

The weight 99, as shown in the drawings, is intended as an emergency means for operating the cross-head 37 in case the air supply to the cylinder 41 should fail. When the cross-head 37 is being operated by compressed air, the table 101 will be detached from the yoke 44 but in case the compressed air supply should fail, the cable 101 may be readily attached to the yoke 44 with very little delay in the operation of the printing press.

Referring now to the invention shown in Fig. 12, parts thereof that are like parts shown in Figs. 1 to 11, inclusive, are given the same reference numeral followed by a prime ('), with the exception that the roll and its web are designated by *y'* and *y''* respectively. In place of the endless friction belt 29, a friction strap 104 is used. One end of the strap 104 is anchored above the roll *y'*, as indicated at 105, and the other end thereof is anchored below said roll, as indicated at 106. This strap 104 between the roll *y'* and its anchored lower end passes around the pulley 31'. The pulley 31' and anchor 105 hold the section of the strap 104 in the same manner in which the belt 29 is held by the pulleys 30 and 31. The section of the strap between the pulley 31' and the anchor 106 is held in the same position as the run of the belt 29 between the pulleys 31 and 32. As the function of the strap 104 is substantially the same as that of the belt 29, it is not thought necessary to describe the action thereof on the roll *y'*.

Operation

It may be assumed that the printing press is stopped and as the web *w* is not being drawn into said press, the roll *y* is idle. Also it may be assumed that the roll *y* is a full roll. The compressor 61 is intermittently and automatically operated by the motor 62 to maintain an air pressure in the supply tank 57 of say ninety (90) pounds. Compressed air from the storage tank 57 is constantly supplied to the cylinder 41 through the pipe sections 58 and 58' and branch pipes 59, and holds the pistons under a minimum pressure of say fifteen (15) pounds. The reducing valve 64 in valve casing 63 is set to maintain this minimum air pressure in the cylinders 41 and enough more to compensate for leakage through the air vent 91 in the valve casing 82 to atmosphere. As the printing press is not running the fluid pump 96 is idle and hence the spring 92 is yieldingly holding the valve 86 closed and the relief valve 87 open.

The governing roll 47 is balanced by the weights 52 to hold the air-reducing valve 71 open to permit air pressure of say thirty (30) pounds through the valve casing 66, which may be assumed to be the desired air pressure to be maintained in the cylinders 41 when the printing press is running at normal or printing speed. However, the air supply from the storage tank 57 to the cylinders 41, through the pipe sections 65, 65' and 58', branch pipes 59 and valve casings 66 and 82, is closed by the valve 86 when the printing press is stopped.

At the time the printing press is stopped, the spring-actuated roll 23 is moved by the springs 28 from its dotted line position to its full line position, see Fig. 1, and takes up any slack placed in the web *w* by movement of the roll *y* under its momentum.

From the above description, it is evident that the roll *y*, when the printing press is stopped, is held under braking action produced by the friction belts 29 on said roll, and said belts are held under tension by the pulleys 31 which are subject to the fifteen (15) pounds of air pressure on the pistons 42.

Upon starting the printing press, the pull thereon on the web *w* will first straighten the run of said web between the directional rolls 24 and 25 and thereby lift the governing roll 47. This lifting of the governing roll 47 will relieve its pressure on the plunger 81 and permit the valve 71 to close or partially close, but this has no effect on the air pressure in the cylinder 41, for the reason that when the valve 86 is closed, the pump 96 has not been operated for a sufficient length of time to build up an air pressure in the cylinder 90 to operate the piston 89 and open the valve 86. The dashpot 53—54 will prevent sudden lifting of the governing roll 47.

Following the lifting of the governing roll 47, the press pull on the web *w* will retract the roll 23 until its actuating springs 28 are compressed approximately fifty per cent (50%). Obviously, the action of the governing roll 47 and the spring-actuated roll 23 on the web *w*, during the initial starting of the printing press, will cause the web *w*, under the pulling action thereon by said press, to gradually overcome the inertia of the roll *y* and start the turning thereof without a sudden pull thereon that would cause the roll *y* to run ahead and put slack in said web. Slack in the web *w* produces an uneven tension thereon and a possible breaking of the web *w* when the slack is taken up by the pull of the printing press.

As the speed of the printing press increases, the pump 96 operates thereby, builds up sufficient air pressure in the cylinder 88 to move the piston 89 and thereby close the valve 87 and gradually open the valve 86. The closing of the valve 87 closes the air escape vent 91 and the opening of the valve 86 gradually increases the air pressure from 45 the storage tank 57 to the cylinder 41 until the air pressure on the pistons 42 has reached the normal maximum air pressure of thirty (30) pounds. It may be here stated that the governing roll 47, immediately after the lifting thereof 50 by the straightening of the respective run of the web *w*, will be returned by gravity to normal position, and thereby resets the valve 71 for air pressure of thirty (30) pounds. During the gradual increase of air pressure in the cylinders 41, 55 by the straightening of the respective run of the web *w*, the tension on the belts 29 is likewise increased thereby, and this increased tension on the belts 29 progressively increases the friction on the roll *y* and hence a greater braking action on the roll *y*, as the lineal travel of the web *w* from the roll *y* 60 to the printing press increases.

As the diameter of the roll *y* is progressively decreased by the unwinding of the web *w* therefrom, the length of the run of the belt 29 between the pulleys 30 and 31 is progressively shortened and 65 this shortening of the respective run of the belts 29 is taken up, as the same develops, by the pulleys 31 which are progressively moved away from the pulleys 32 by air pressure in the cylinders 41 acting on the pistons 42.

70 It was heretofore stated that a progressively

decreasing effort was required to control the roll y as the diameter thereof progressively decreased, and this decreasing diameter of the roll y progressively decreased the length of the circumferential wrap of the belts 29 on the periphery of the roll y . As the decreasing length of the wrap of the belts 29 on the roll y is somewhat greater than the effort desired to control the roll y in its highest efficiency, the length of this wrap is progressively decreased as the diameter of the roll y decreases, by moving the pulleys 31 farther away from the pulleys 32. In other words, the pulleys 31 are moved farther under the roll y and away from the side of said roll from which the web w is leaving the same as the diameter of the roll decreases.

The novel arrangement of the pulleys 30, 31 and 32, relative to the roll y , is highly important and particularly where one of the two pulleys, that holding the end portions of the respective run of the belt 29 tangentially to the roll on opposite sides thereof, and with the intermediate portion of said run wrapped circumferentially on the periphery of said roll, is automatically moved bodily outwardly with the respective tangential end portion of the web as the same progressively lengthens under the action of the progressively diminishing diameter of the roll y , as its web w is unwound therefrom. This bodily movable pulley not only progressively decreases the length of the circumferential wrap of the belt with the roll, as the diameter of said roll progressively decreases, but due to its close proximity to the roll y , is very sensitive to any tension variation in the run of the belt 29 contacting the roll y , due to an unevenly wound roll or other causes, and automatically compensates therefor and keeps the respective run of the belt 29 under a constant and even tension.

As the belts 29 are spaced edgewise apart axially of the roll y and substantially equal distances apart, and as each thereof is independently and automatically controlled, the frictional contact between the roll y and belts 29 is the same at all contacting points so that the roll y is evenly controlled throughout its entire length.

In case the printing press is suddenly stopped, the momentum of the roll y will put slack in the web w and cause the governing roll 41 to drop by gravity which, together with the retracted spring-pressed roll 23, will take up this slack. This dropping of the governing roll 41 will force the plunger 81 downwardly and thereby further open the valve 71 and allow an increased air pressure to flow from the storage tank 57 to the cylinders 41. This increased air pressure in the cylinders 41 will press the pistons 42 further downwardly in said cylinders and thereby increase the tension on the belts 29 and hence the friction or braking effort on the roll y , and thereby prevent further turning thereof under momentum.

At the time the active roll y is expiring, the pistons 42 are at their lowermost positions in the cylinders 41 and the run of the belts 29 between the pulleys 30 and 31 is at its shortest length. As the roll y is expiring, the reel 17 is operated to move the new full roll z into the place of the expired roll y . Swinging the roll z from its idle position to its active position will cause the same to engage the runs of the belts 29 between the pulleys 30 and 31 and thereby draw the belts over the pulley 31 and away from the pulleys 32.

This movement of the belts 29 increases the length of its runs between the pulleys 30 and 31 to their maximum length and also moves the

cross-heads 37 and the pulleys 31 mounted therein upwardly in the cross-head guides 38. Movement of the cross-heads 37 upwardly in the cross-head guides 38 moves the pistons 42 upwardly in the cylinders 41 and thereby produces back pressure and forces the air in said cylinder through the branch pipes 59, pipe sections 58' and 65', valve chamber 83, pipe section 65' and into the valve chamber 69, where the same lifts the diaphragm 67, opens the valve 74 and allows the air to escape through the port 73 to the chamber 68 and from thence through the holes 78 to atmosphere. As the diaphragm 67 is lifted by back air pressure, the spring 76, acting on the valve carrier 75, closes the valve 71. As soon as air pressure in the chamber 69 is reduced to normal, the diaphragm 67, acted on by the spring 79, closes the valve 74 and opens the valve 71.

In place of the cylinders 41 and the co-operating pistons 42, the cross-heads 37 may be operated by means of the weight 99. In case air pressure to the cylinders 41 should fail, the change from air pressure to the weight 99 only necessitates the attachment of the cable 100 to the yokes 44.

It is, of course, understood that the anchored straps shown in Fig. 12 may be used in place of the belts 29 or a combination of said straps and belts used.

The automatically controlled variable braking effort I use in connection with the roll of paper, as its web is being drawn into a printing press and the tension on said web is highly important during acceleration, normal running speed and deceleration of a printing press or the sudden stopping thereof. This invention is especially efficient during the preparation of a printing press for running when it is necessary to make many starts and stops of said press during plating thereof. During this plating-up process, the pull of the press on the web of paper is uneven due to the plates being unevenly distributed on the cylinders. If the tension on the web of paper were as great during the time the press is being plated as it is when the press is running, then said web would break due to the uneven pull thereon, thus causing waste and delay.

By manipulating the hand valves 60, the air pressure in the cylinders 41 may be manually controlled, at will.

The drawings illustrate a commercial form of the invention, but it will be understood that the same is capable of a large range of modifications within the spirit of the invention herein disclosed and broadly claimed.

What I claim is:

1. Mechanism for controlling a roll of web material and tensioning its unwound web between said roll and a printing press or other machine into which said web is fed, comprising a friction strap-like member, a pair of devices for holding said member, means for supporting a roll of web material between said devices, a bodily movable direction-changing device engaging said member, forming a loop therein between one of the devices of said pair and the roll and holding a section of said member bowed and wrapped circumferentially around the periphery of the roll, and means operable on the direction-changing device for holding said member under tension and for moving the direction-changing device in a direction to decrease the circumferential wrap of said member on the roll as the diameter of said roll is decreased by unwinding its web therefrom, the operating means for the direction-changing

device holding said friction member under a pre-determined minimum tension when the machine is stopped, and including mechanism, controlled by a part of the machine that moves at a variable speed, for progressively increasing the tension on said member during acceleration of the machine, holding said member at a predetermined tension during normal running of the machine and progressively decreasing said tension during deceleration of the machine.

2. Mechanism for controlling a roll of web material and tensioning its unwound web between said roll and a printing press or other machine into which said web is fed, comprising a friction strap-like member, a pair of devices for holding said member, means for supporting a roll of web material between said devices, a bodily movable direction-changing device engaging said member, forming a loop therein between one of the devices of said pair and the roll and holding a section of said member bowed and wrapped circumferentially around the periphery of the roll, and means operable on the direction-changing device for holding said member under tension and for moving the direction-changing device in a direction to decrease the circumferential wrap of said member on the roll as the diameter of said roll is decreased by unwinding its web therefrom, the operating means for the direction-changing device holding said friction member under a pre-determined minimum tension when the machine is stopped, and including mechanism, controlled by a part of the machine that moves at a variable speed, for progressively increasing the tension on said member during acceleration of the machine, holding said member at a predetermined tension during normal running of the machine and progressively decreasing said tension during deceleration of the machine, said operating means further including other mechanism, controlled by the tension of the web, for increasing the tension on said member during normal running of the machine in case tension on the web drops below a predetermined tension.

3. Mechanism for controlling a roll of web material and tensioning its unwound web between said roll and a printing press or other machine into which said web is fed, comprising a friction strap-like member, a pair of devices for holding said member, means for supporting a roll of web material between said devices, a direction-changing pulley engaging said member, forming a loop therein between one of the devices of said pair and the roll and holding a section of said member bowed and wrapped circumferentially around the periphery of the roll, a cross-head on which the pulley is journaled, a guide for the cross-head, and means operative on the cross-head for holding said member under tension, said guide being arranged to direct the pulley to progressively decrease the circumferential wrap of said member on the roll as the diameter of said roll is progressively decreased by unwinding its web therefrom.

4. Mechanism for controlling a roll of web material and tensioning its unwound web between said roll and a printing press or other machine into which said web is fed, comprising a friction strap-like member, a pair of devices for holding said member, means for supporting a roll of web material between said devices, a bodily movable

direction-changing device engaging said member, forming a loop therein between one of the devices of said pair and the roll and holding a section of said member bowed and wrapped circumferentially around the periphery of the roll, a co-operating cylinder and piston for moving the direction-changing device in a direction to progressively decrease the circumferential wrap of said member on the roll as the diameter of the roll is progressively decreased by the unwinding of its web therefrom, a source of fluid under pressure, and means for supplying fluid from said source to the cylinder.

5. The structure defined in claim 4 in which the means for supplying fluid to the cylinder further includes a reducing valve.

6. The structure defined in claim 4 in which the means for supplying fluid to the cylinder further includes a reducing valve, and means controlled by the tension of the web for holding the reducing valve in a predetermined open position.

7. The structure defined in claim 4 in which the means for supplying fluid to the cylinder further includes a reducing valve, and means controlled by the tension of the web for holding the reducing valve in a predetermined open position and for opening the reducing valve to a greater fluid-conducting capacity when the tension on the web is reduced below a predetermined tension.

8. The structure defined in claim 4 in which the means for supplying fluid to the cylinder further includes a reducing valve and a relief valve.

9. Mechanism for controlling a roll of web material and tensioning its unwound web between said roll and a printing press or other machine into which said web is fed, comprising a friction strap-like member, a pair of devices for holding said member, means for supporting a roll of web material between said devices, a bodily movable direction-changing device engaging said member, forming a loop therein between one of the devices of said pair and the roll and holding a section of said member bowed and wrapped circumferentially around the periphery of the roll, a co-operating cylinder and piston for moving the direction-changing device in a direction to lengthen said loop and thereby progressively decrease the circumferential wrap of said member on the roll as the diameter of the roll is progressively decreased by the unwinding of its web therefrom, a source of fluid under pressure, means for supplying fluid from said source to the cylinder, at a relatively low pressure, and further means controlled by a part of said machine that moves at a variable speed for supplying fluid from said source to the cylinder at a pressure that progressively increases from said low pressure up to a maximum pressure during normal running of the machine, and that progressively decreases to said low pressure during deceleration of said machine.

10. The structure defined in claim 9 in which the means for supplying fluid from said source further includes a reducing valve, and means controlled by the tension of the web for holding said valve open at substantially said maximum pressure and for opening said valve to a greater fluid-conducting capacity when the tension on the web is reduced below a predetermined tension.
